CLAIM

The ornamental design for a gasoline container, as shown and described.

DESCRIPTION

FIG. 1 is a right side view of a gasoline container according to a preferred embodiment of the design;

FIG. 2 is a left side view of the embodiment of the design that is depicted in FIG. 1;

FIG. 3 is a front view of the embodiment that is depicted in FIGS. 1 and 2;

FIG. 4 is a rear view of the embodiment of the design that is depicted in FIGS. 1 through 3;

FIG. 5 is a top view of the embodiment of the design that is depicted in FIGS. 1 through 4; and,

FIG. 6 is a bottom view of the embodiment of the design that is depicted in FIGS. 1 through 5.

The broken lines are shown in the views for illustrative purposes only and form no part of the claimed design.
